UNITED STATES PATENT OFFICE.

EDMUND R. BARANY, OF BROOKLYN, NEW YORK, ASSIGNOR TO FRENCH BATTERY COMPANY, OF MADISON, WISCONSIN, A CORPORATION OF WISCONSIN.

ELECTRIC SWITCH.

Application filed June 13, 1926. Serial No. 116,773.

This invention relates to electric switches and is herein shown embodied in a flashlight of the so-called "focusing" or "spotlight" type.

5 The invention embodies certain improvements in the structure shown in my co-pending application Serial No. 77,487, filed December 24, 1925, and also includes novel means for removably locking the switch unit 10 within a flashlight casing in such a way as to permit relative axial adjustment between the flashlight reflector and the flashlight lamp.

15 The nature, objects and advantages of the invention will become apparent from the following description taken in connection with the accompanying drawings in which—

20 Figure 1 is a view partly in section and partly in elevation of a flashlight casing with which is associated one form of switch unit embodying the invention, the switch unit being shown in elevation.

25 Figure 2 is an enlarged fragmental longitudinal sectional view of a flashlight in which the switch is shown in open-circuit position.

30 Figure 3 is a view similar to Figure 2 but showing the switch in closed-circuit position.

35 Figure 4 is a view similar to Figure 3 showing the position that the switch unit assumes as it is introduced into or removed from the flashlight casing.

40 Figure 5 is an end view of the flashlight casing and switch unit as seen from above in Figure 4.

45 Figure 6 is a sectional view of the switch unit removed from the flashlight casing, the section being taken on line 6—6 of Figure 4.

50 Figure 7 is a plan view of the switch unit shown in Figure 6.

55 Figure 8 is a modified form of the switch unit in which the switch-operating member is only pivotally connected to its support.

Referring to the drawings, the casing 5 of the flashlight, herein shown as of the focusing type, with which the switch unit embodying the invention is adapted to be used, 50 is formed with a groove 6 with which certain locking elements of the unit, herein-after more particularly described are adapted to cooperate for locking the unit within the casing 5. In the type of flashlight here- 55 in shown, the reflector assembly, comprising

the usual lens 8, hood 9, lens ring 10 and reflector 11 through which the flashlight lamp 12 projects, is carried upon the screw-threaded end 13 of the casing 5 and is adapted for axial adjustment thereon so that the 60 reflector 11 may be focally adjusted with respect to the lamp 12.

The switch unit is adapted to be assembled exteriorly of and thereafter introduced into the casing 5, within which it is retained 65 with a portion of its switch member 15 projecting through an elongated opening 16 formed in the casing 5 adjacent the screw-threaded end 7 thereof. The switch member includes an operating member 17, formed 70 with a notch 18, and carrying a pair of yieldable contacts 19 and 20 electrically connected together by means of a strap 22 riveted or otherwise secured to the operating member 17. The contacts 19 and 20 are 75 substantially U-shaped, the free end of the latter being movably retained within the notch 18. The inner end of the operating member 17 is beveled and is adapted to cooperate with a spring arm 23, herein shown 80 as formed integral with a retaining element 25 carried by a suitable support 26 and adapted to enter the groove 6. The support 26 is in the form of a yoke, the depending 85 legs 27 of which are substantially V-shaped and are provided with outwardly turned feet 28 to which a disc 29 of insulating material is suitably connected, the disc 29 being provided with a contact element 30 adapted 90 to engage the carbon electrode 31 of a flashlight battery B, having its zinc electrode 32 connected to the casing 5 through the usual compression spring 33 and screw-threaded end cap 34.

To the upper end of the support 26 is suitably connected a lamp socket 36 adapted for the reception of the flashlight lamp 12, the outer terminal 37 of the lamp being thus electrically connected with the socket 36 and the central terminal 38 of the lamp being so 100 exposed as to cooperate directly with the contact 20 when the operating member 17 is moved to the position shown in Fig. 5 in which the circuit is closed through the battery B and lamp 12. Upon the support 26 105 is rotatably mounted a locking element 40, the outer end of which is adapted to enter the groove 6 at a point diametrically opposite the locking element 25, to initially retain the switch unit properly positioned 110

within the casing 5. While the switch unit is being introduced into the casing 5, the locking element 40 is positioned as shown in Figure 4, and the unit assumes the inclined 5 position, also shown in Figure 4, thereby allowing the operating member 17 to enter the opening 16 so as to permit the unit to be manipulated into its operative position in the casing, after which the locking element 10 40 is rotated about the socket 36 until its outer end engages the groove 6 in the casing at a point diametrically opposite the point at which the retaining element 25 engages said groove, thereby not only initially locking 15 the unit within the casing but also centering the unit therein. After thus initially locking the unit within the casing, a screw-threaded cup-shaped hold-down element 42 may be run down over the lamp socket 36 20 and into engagement with the upper face of the rotatable locking element 40. In order to prevent rotation of the locking element 40 as the hold-down element 42 is urged into intimate engagement with the locking element 25, the support 26 is provided with an upturned stop or lug 43 with which the locking element 40 is adapted to engage.

In the preferred form of the invention shown in Figs. 1 to 7, the upper end of the 30 slot in the casing 5 is engaged by the protruding end of the switch member when the latter is in open-circuit position, thereby preventing accidental movement of the switch member to closed-circuit position. As shown 35 in Figures 1 and 2, the spring 23 tends to retain the switch member in its protruding position, and in order to close the circuit through the battery B and lamp 12, movement in two general directions of the switch 40 member is required, one movement being slidable and the other pivotal. In order to provide for such movement, the switch member is both pivotally and slidably connected to the support 26, by reason of the fact that 45 it is mounted on a rivet 45, secured to the legs 27 of the support and passing through an elongated opening 46 formed in the operating member 17. The spring 23 tends not only to maintain the switch member projected, as shown in Figures 1 and 2, but it 50 also exerts upon the end of the switch member a thrust, off-center with respect to the bearing 45 in the direction of arrow C in Fig. 1, and thereby tends to retard rotation 55 of the switch member in closing the circuit, until such time as the switch member has been so rotated that the thrust upon its bevelled end by the spring 23 is exerted upon the opposite side of the center of rotation in 60 the direction of arrow D in Figure 3. The thrust thus exerted by the spring 23 tends to retain the switch member in closed-circuit position; and in addition to this thrust, a further thrust exerted by the contact 20 in 65 the direction of arrow E in Figure 3 to the

left of the point of rotation of the switch member 17 also tends to retain the switch member in closed-circuit position. These thrusts exerted in the directions of arrows D and E in Fig. 3 are sufficient to overcome 70 any thrust exerted by the resilient contact 19 which may tend to move the switch member out of closed-circuit position.

Referring to Figure 8 wherein a modified form of the invention is shown, the switch member instead of being both pivotally and slidably connected to the support 26 is only pivotally connected to said support. This arrangement necessitates so proportioning the protruding end of the switch member 75 that it is free to clear or pass by the casing 5 when moving the switch member to closed circuit position. In the absence of cooperation between the casing 5 and the operating member, such as exists in the structure shown 80 in the preferred form of the invention to insure against accidental movement of the switch member from open-circuit position, the spring 23 is depended upon to exert a sufficient thrust upon the switch member in 85 the direction of arrow C' to eliminate, under normal conditions, the possibility of accidental movement of the switch member to closed-circuit position.

The modified form of the invention, 90 shown in Figure 8, further differs from the preferred form, in that the insulating disc 29 and the contact element 30 are eliminated so that the contact 19 engages and cooperates directly with, rather than indirectly 100 with, the carbon electrode 31 of the flashlight battery.

To close the circuit through the battery B and lamp 12 when the preferred form of the invention shown in Figures 1 to 7 is employed, the switch member is first moved against the influence of the spring 23 a sufficient distance to permit the protruding end of the switch member to clear the casing 5, whereupon the switch member is moved 110 about the bearing 45 as a pivot. As the switch member is pivotally moved, the contact 20 moves into engagement with the central terminal 38 of the lamp 12 and may slightly pass the center thereof, the free end 115 of the contact 20 confined within the notch 18 being permitted, due to the yielding of the contact 20, to assume the position shown in Figure 3. As soon as the contact 20 engages the central terminal 38 of the lamp 12, a circuit is closed through the carbon electrode 31, contact element 30, contact 19, strap 22, contact 20, lamp terminal 38, lamp filament not shown, lamp terminal 37, lamp socket 36, locking elements 40 and 25, casing 120 5, end cap 34, thrust spring 33 and the zinc electrode 32 of the battery B. When it is desired to open the circuit just described, the switch member is swung about its bearing 45 into alignment with the opening 16, 125 130

whereupon the spring 23, exerting a thrust upon the switch member, moves the protruding end of the switch member through the opening 16 into its position shown in Figures 1 and 2.

In closing a circuit through the battery and lamp when the modified form of switch unit shown in Figure 8 is employed, the switch member is simply rotated so as to move the contact 20 into engagement with the central terminal 38 of the lamp whereupon the carbon electrode 31 of the battery is connected with the lamp directly through contact 19, strap 22 and contact 20, the remainder of the circuit being the same as that above described. Upon moving the switch member to closed-circuit position, the spring 23 functions to hold the switch member in closed circuit position in the same manner as described in connection with the preferred form of my invention, and as above explained the spring 23, exerting a thrust upon the switch member in the direction of the arrow C', is depended upon, in the absence of any cooperation between the switch member and casing 5, to normally retain the switch member in open-circuit position.

What is claimed is:

1. A switch unit adapted to be used in a flashlight and comprising a support, a contact element carried by said support and insulated therefrom and adapted to engage a terminal of the flashlight battery, and a switch member pivotally connected to said support and including a pair of yieldable contacts one of which engages said contact element and the other of which is adapted to engage a terminal of the flashlight lamp in closing a circuit through said battery and said lamp.

2. A switch unit adapted to be used in a flashlight including a casing having an opening, said unit comprising a support, a switch member movably connected to said support and adapted to project through said opening, said switch member having a notch formed therein and including a pair of yieldable contacts adapted to be placed in circuit with the lamp and battery, one end of one of said contacts being movably confined within said notch.

3. A flashlight-casing and a switch-unit insertable in said casing through the open end thereof, said switch-unit comprising a support, a switch-lever, and locking means carried by said support and including relatively rotatable locking elements adapted to cooperate with the flashlight-casing to lock said unit in said casing, one of said locking elements being pivotally connected with said support.

4. A flashlight-casing and a switch-unit insertable through the open end of said casing, said casing having an internal groove near one end and said switch-unit comprising

ing a support, a switch-lever mounted on said support, and locking means carried by said support comprising relatively rotatable locking elements adapted to cooperate with the groove in said casing to lock said switch-unit therein, one of said locking elements having a pivot co-axial with respect to the axis of said casing.

5. A flashlight-casing and a switch-unit as specified in claim 3, in combination with a removable supplemental locking-member having threaded connection with said casing and having engagement with said support.

6. A switch-unit adapted to be inserted in a flashlight-casing, said switch-unit comprising a support, a contact-element carried by the lower end of said support and insulated therefrom and adapted to engage the central terminal of the adjacent dry-cell, a lamp-bulb carried by the upper portion of said support, a switch-member interposed between the lamp-bulb and said contact-element and movably connected to said support, and a pair of contacts mounted on said switch-member, one of which contacts is adapted to engage said contact-element and the other of which is adapted to engage the terminal of the lamp-bulb.

7. A switch-unit for the purpose set forth, comprising a support equipped with means for locking it within a flashlight-casing and equipped at its upper portion with a lamp-bulb socket, and a switch-lever pivotally mounted in said support, said switch-lever having a handle adapted to project laterally through an opening in the casing and being equipped with a pair of resilient contact-members, one of which is adapted to engage the terminal of a lamp-bulb when mounted in said socket and the other of which is adapted to establish the circuit to the central contact of a dry-cell when located within the casing of a dry-cell.

8. In combination, a flashlight-casing; a switch-unit within said casing comprising a support equipped at its upper end with a lamp-bulb socket, means for anchoring said support within said casing, a pivoted switch-lever equipped with a resilient contact adapted to make contact with the lamp-bulb and equipped also with a resilient contact through which the circuit to the central contact of the dry-cell may be established, and a supplemental locking-member threaded within the upper portion of the casing and having a member provided with a central opening through which said socket extends.

9. In combination, a flashlight-casing; a switch-unit within said casing comprising a support equipped at its upper end with a lamp-bulb socket, means for anchoring said support within said casing, a pivoted switch-lever equipped with a resilient contact adapted to make contact with the lamp-bulb

and equipped also with a resilient contact through which the circuit to the central contact of the dry-cell may be established, a reflector above said socket having an opening 5 through which the lamp-bulb may extend freely, and an adjustable ring carrying said reflector and having threaded engagement with the upper portion of said casing.

10. A flashlight casing and a switch-unit 10 adapted to be used therein, said unit comprising a support having means for control-

ling a lamp circuit, locking means carried by said support and including relatively rotatable locking elements adapted to cooperate with the flashlight casing to lock said unit in said casing, and a removable supplemental locking member having threaded connection with said casing and having engagement with said support. 15

In testimony whereof, I have affixed my 20 signature to this specification.

EDMUND R. BARANY.
